(54) **SAW MILL STRAP**

(76) Inventor: **Othniel Stone**

Othniel Stone
Patent

The schedule referred to in these Patents and making part of the same containing, a description in the words of the said Othniel Stone himself, of his improvement in saws mills & sawing, Machines called the Sheep Saw.

To all persons to whom these patents shall come

Othniel Stone of the town of Pittsford in the County of Monroe and State of New York send greeting.

It is known that I, Othniel Stone have invented and applied to use new and usefull improvements in saw mills and sawing Machines called Sheep Saw & are specified together with the saw in the records following. The saw containing, said improvement is made in the form of a hoop or ring, and may be made any number of feet in circumference according to the purpose to which it is to be applied, and the saw-plate may be of any width or thickness. The size of the saw selected for description herein is nine feet in circumference. There is no width and the thickness of a thin wood saw, but the circumference of the saw, the width and thickness may according to circumstances. The saw is hung around two wheels or drums eighteen inches in diameter and three inches thick with a wire one fourth of an inch raised above the wheel or drum for the back of the saw, to run against, to prevent the saw from running off the wheel or drum which wheel or drum are to be placed the one directly over the other but the wheels or drums may be any other diameter or thickness or the wire raised less or more than one fourth of an inch according to most convenient. The above description applies to a saw with teeth on one edge only. The saw may be made

Made with teeth on both edges so as to saw both ways, in which case the wheels or discs will be made with eyes in the center of the wheels or discs two inches apart and one fourth of an inch square at the surface and tapering towards the outer edge with square holes in the base two inches apart and one fourth of an inch square to keep the disc either in the direction from slipping either way on the wheels or discs, but the eyes may be put any distance apart and any size or provided they secure the saw, when in motion, from slipping on the wheels or discs, and the wheels or discs may be any thickness, but if they are thicker than the width of the saw, it will be necessary, that the part of the wheels or discs directly under of the teeth of the saw, be made less than the rest of the wheels or discs so as to prevent the same from taking the set out of the saw. The wheels may be made of wood or iron or any kind of metal or part wood and part iron or metal. If the wheels or discs be made of iron or any kind of metal the same may be covered with leather so that the outer edge or edge may be pointed or cut down as the saw goes, measured by the saw to be kept steady by means of two pairs of rollers, the lower pair stationary, and the upper pair moveable. The lower pair of rollers will be placed directly under and as near as may be to the timber or wood to be sawed, and the upper roller will be placed directly over the timber or wood to be sawed with a slide to make it up or down as the thickness of the timber or wood to be sawed may require which rollers may be made of wood or iron or part wood & part iron & to be strong as the saw is wide and the rollers of each pair to be far enough apart to let the saw pass between them and make a little snath, where the saw teeth are so set to take the set out, which rollers may be an inch or more in diameter. If it should be necessary one

or more set of rollers may be utilized to keep the saw steady, or from wobbling. The saw may be driven by the application of hand, horse, steam, or water power and applied to the sawing of mill logs of any dimensions, slitting, sawing, mincing, sawing wood, or any kind of sawing whatever.

Where the saw is stretched upon the wheel it occurs the sides will be flattened. The specific uses and useful improvements herein before described and claimed by me as the invention are the following. First: the shape of the saw; second: the manner of hanging the saw. Third: the manner of keeping the saw steady when in motion by means of rollers. Fourth: the manner of marking the saw with teeth on one or both edges.
